UNITED STATES PATENT OFFICE.

NEWBURY M. MERRITT, OF NORWALK, CONNECTICUT.

MILK-BOTTLE OPENER AND STOPPER.

1,173,832.

Specification of Letters Patent.

Patented Feb. 29, 1916.

Application filed May 5, 1915. Serial No. 26,056.

To all whom it may concern:

Be it known that I, NEWBURY M. MERRITT, a citizen of the United States, residing at Norwalk, in the county of Fairfield, and 5 State of Connecticut, have invented new and useful Improvements in Milk-Bottle Openers and Stoppers, of which the following is a specification.

Milk bottles at present are generally 10 closed by means of a pasteboard disk seated upon an internal annular shoulder disposed a slight distance below the mouth of the bottle. It is a common practice to remove these stoppers by pushing one side of the 15 disk within the bottle by means of the thumb, elevating the other side to permit the same to be gripped by the fingers. During this operation an appreciable amount of dust and other foreign matter that collects 20 upon the disk enters the bottle and is mixed with the contents thereof, which is both objectionable and unsanitary. These conditions become more highly objectionable by 25 the continued handling of the stopper, in removing the same from and replacing the stopper upon the bottle whenever the necessity arises for pouring out more of the milk.

It is the primary object of the present invention to provide an instrument in the 30 nature of a combined disk extractor and stopper, whereby the disk can be removed without handling the same, and the device used as a temporary stopper, thus providing for the disposal of the disk subsequent to its 35 removal.

Specifically stated the invention essentially consists of a tapered body portion forming a stopper, and an extracting element comprising a single length of material 40 passed through the body and terminally formed to provide a laterally extending prong disposed below the body and a looped handle portion disposed above the body for manipulating the device.

Another object of importance resides in 45 threading that portion of the element disposed below the body, and having a nut adjustably mounted thereon, whereby the said element may be drawn downwardly 50 through the body upon adjustment of the nut, with a view of holding the said looped handle partly embedded in the body to prevent turning of the element therein.

In the drawing forming a part of this

application like numerals of reference indicate similar parts in the several views and wherein:—

Figure 1 is a sectional view through the bottle showing the manner of using the device. Fig. 2 is a perspective view of the 60 device. Fig. 3 is a vertical sectional view therethrough.

Referring more particularly to the drawing 5 indicates the body portion of the device constituting a temporary stopper for 65 the bottle 6 subsequent to the removal of the disk 7 therefrom. The body portion 5 may be constructed from any suitable material, preferably of some composition possessing minimum resiliency, and tapered to 70 the desired degree as in the manner of the ordinary and well known form of stopper.

Passed axially through the body portion 5 is an extracting element 8, comprising a single length of suitable material, preferably 75 wire, having its lower end bent to provide a laterally extending pointed prong 9 disposed below and in spaced relation to the lower end of the body portion 5, while the opposite end of the wire terminates to provide 80 a looped handle portion 10 adapted to be grasped by the user for manipulating the device, the loop being disposed in the same vertical plane with the prong 9 to permit a natural movement of the hand while 85 extracting the disk from the bottle. The portion of the element projecting below the body portion 5 is threaded as at 11, and adjustably mounted thereon is a nut 12, whereby the element may be drawn downwardly 90 through the body portion upon adjustment of the nut, with a view of partly embedding the looped handle portion 10 in the body portion 5 so as to prevent turning or twisting 95 of the element within said body.

In use of the device, the prong 9 is forced through the pasteboard disk and arranged to engage the underside thereof, so that lifting of the instrument will readily and easily remove the disk from the bottle as will be 100 obvious. Should only a part of the contents be removed from the bottle and it be necessary to again close the bottle, the disk together with the device may be replaced upon the shoulder 13 of the bottle 105 in the usual manner. Or the disk may be removed from the prong 9 and the body portion 5 inserted within the mouth of the

bottle and used as a temporary stopper. During this use of the device the shoulder 14 thereof provided by the reduced lower portion 15 is adapted to engage the shoulder 5 13 of the bottle with a view of preventing dirt, dust or foreign matter from collecting about the mouth of the bottle, or entering the same upon removal of the stopper therefrom. The prong 9 is so disposed so 10 as not to contact the wall of the bottle when the device is used as a temporary stopper, and as will be readily understood, after an appreciable amount of milk has been removed from the bottle the metal prong does 15 not extend far enough within the bottle to come in contact with any of the contents thereof.

It is believed that from the foregoing description the nature and advantages of the 20 invention will be thoroughly understood without requiring a more extended explana-

tion and therefore the same has been omitted.

What is claimed is:—

As a new article of manufacture, a combined stopper and disk remover comprising a tapered body portion, an extracting element passed through said body and formed at one end to provide a laterally extending prong disposed below and in spaced relation to the body, the opposite end of said element forming a loop disposed above the body, said element having a threaded portion, and a nut adjustably associated therewith to retain said loop partly embedded in said body for the purpose specified. 35

In testimony whereof I affix my signature in presence of two witnesses.

NEWBURY M. MERRITT.
